UNITED STATES PATENT OFFICE.

FRANKLIN E. ARNDT, OF GALION, OHIO, ASSIGNOR OF ONE-HALF TO DAVID C. BOYD,
OF GALION, OHIO.

FUEL-VAPORIZER.

1,278,557.

Specification of Letters Patent. Patented Sept. 10, 1918.

Application filed December 26, 1917. Serial No. 208,927

To all whom it may concern:

Be it known that I, FRANKLIN E. ARNDT, a citizen of the United States, residing at Galion, in the county of Crawford and State of Ohio, have invented certain new and useful Improvements in Fuel-Vaporizers, of which the following is a specification.

This invention relates to an improved vaporizer for hydrocarbon fuels and in its generic aspect, contemplates the provision of means for thoroughly vaporizing the heavier relatively low grade hydrocarbon fuels such as kerosene and the like, as well as improving and increasing the vaporization of high grade fuels, such as gasolene, and securing the maximum amount of completely vaporized mixture from any fuel used, so that they may be utilized in the operation of motor vehicle engines.

It is another object of the invention to provide a vaporizer for the above purpose which may be used as an adjunct to the intake and exhaust manifold with which the engine is equipped, or may itself constitute the intake and exhaust manifold.

It is one of the detail objects of my invention to provide a fuel vaporizer including generally an outer shell or casing within which is formed separate exhaust receiving chambers corresponding in number with the number of exhaust ports of the engine, said casing also having intake port connections and means for causing a circulation of the charge around and in contact with the walls of said exhaust chambers prior to its admission to the intake ports of the engine cylinders.

It is also an important object of my invention to provide in a vaporizing apparatus as above characterized, means whereby an equal distribution of the vaporized mixture to the intake ports of the engine cylinders may be effected.

And it is a further general object of my invention to provide a hydrocarbon fuel vaporizer which is relatively simple in construction as well as effective and reliable in practical use, may be readily applied to the various types of motor vehicle engines, and by the use of which appreciable economy may be realized in the operation of the engine.

With the above and other objects in view, the invention consists in the novel features

of construction, combination and arrangement of the several parts as will be herein-after more fully described, subsequently claimed and illustrated in the accompanying drawings, in which similar reference characters designate corresponding parts throughout the several views and wherein.

Figure 1 is an elevation partly in section showing my improved vaporizer applied to a motor vehicle engine in conjunction with intake and exhaust manifolds, such for instance as are found in the Ford type of engine;

Fig. 2 is a transverse section taken on the line 2—2 of Fig. 1;

Fig. 3 is a vertical section taken on the line 3—3 of Fig. 1;

Fig. 4 is a top plan view partly in section;

Fig. 5 is a side elevation showing the vaporizer used as a substitute for the intake manifold.

Referring in detail to the drawings, 5 designates the outer shell or casing of the vaporizer which, for purposes of illustration I have herein shown as operatively applied to a four cylinder engine.

The shell or casing 5 is preferably formed with longitudinally tapering end portions 6 which are divided from the body portion of the casing by vertical partitions 7. In spaced relation to each of these partition walls 7, a continuous transverse wall 8 integrally connects the opposite side walls of the casing and incloses or defines the exhaust receiving chamber 9 which is preferably of rectangular form and has its longer dimensions extending longitudinally of the casing. The top and bottom walls of this chamber are equidistantly spaced from the corresponding walls of the outer shell or casing 5 to provide passages for the mixture, as will be hereinafter more fully related.

Between each of the vertical partition walls 7 and the opposed end wall of the chamber 9 and integrally connecting said walls there is a centrally located vertically disposed baffle plate 10, which is of a height slightly less than the space between the top and bottom walls of the chamber 9. The upper and lower ends of the baffle plate 10 are integrally connected to the relatively opposite side walls of the casing 5 by the transverse webs 11 which are likewise in-

tegral with the end wall of the exhaust receiving chamber and with the partition wall 7.

One side wall of the casing 5 is formed 5 with exhaust inlet openings 12 and 13 which respectively communicate with the hollow tapered ends of the casing 5 and with the spaced chambers 9. Bored lugs 14 and 15 respectively are integrally formed on the 10 partition walls 7 and upon the walls 8 and are adapted to receive the usual attaching bolts whereby the shell or casing is securely fixed in position with the openings 12 and 13 in connection with the exhaust ports of 15 the engine cylinders. In the opposite side wall of the casing 5 the outlet openings 16 and 17 respectively for the exhaust gases are provided and to these openings, the exhaust manifold indicated at 18 is connected 20 through which the exhaust gas is delivered to the muffler.

19 designates the intake openings in one side wall of the casing 5 which register with the intake ports of the engine cylinders, and 25 similar openings 20 are provided on the opposite side of the baffle wall 10 in the other side wall of the casing 5. To these latter openings, the intake manifold 21 leading from the carburetor is connected.

30 In the operation of the device as above described, it will be understood that the exhaust gases from the engine cylinders are delivered through the ports 12 and 13 into the tapering ends of the casing 5 and the 35 several chambers 9. Thus the walls of these chambers and the partition walls 7 become highly heated as the gas expands in the several chambers. It will be understood that there is no impediment to the passage of the 40 gases, which enter the exhaust manifold 18 through the openings 17. The walls 7 and 8 are however heated to a very high degree. The kerosene or other low grade hydrocarbon fuel mixture enters the casing 5 through 45 the openings 20 from the intake manifold and is delivered against the baffle plates 10. The suction through the intake openings 19 in the operation of the engine, draws the fuel gas longitudinally beneath the chamber 50 walls 8 to the center of the casing 5, then upwardly between these chambers and longitudinally over the chamber walls, and finally downwardly on the opposite sides of the baffle plates 10 through the ports 19 to 55 the engine cylinders. This circuitous course of the mixture in its travel through the vaporizer casing 5, results in the thorough vaporization of all solid particles of the liquid fuel, which result is further assured by the 60 concentration of the mixture between the opposed ends of the chambers 9 and the subjection of the mixture in its upward passage to the combined heat from these opposed end walls of the exhaust chambers. At the top 65 of the chambers 9 and at the center of the

casing 5 the division of the mixture occurs, and it is drawn in substantially equal volume in opposite directions over the top walls of the chambers 9 to the respective intake openings 19. In this manner, it will be appreciated that kerosene and other relatively heavy fuels can be satisfactorily used as the propelling medium for motor vehicle engines and owing to the complete vaporization of such hydrocarbon fuel, perfect combustion in the engine cylinder may be obtained.

For the purpose of quickly starting the cold motor, I provide upon the top wall of the casing 5 immediately above each of the 80 baffle plates 10, a priming cup 22 through which gasoline or similar refined hydrocarbon fuels may be initially supplied to the engine cylinders. Of course after the engine has been started and the walls 7 and 8 have 85 become sufficiently heated, the operation of the engine is continued with the use of the low grade fuel.

In Fig. 5 of the drawings I have shown my improved vaporizer applied to the engine cylinder as a substitute for the usual intake manifold. In such construction, the bottom wall of the casing 5 is formed with a goose neck extension 23 for connection to the carburetor. This gooseneck extension 95 is preferably integral with the casing wall at the center thereof and delivers the mixture against the bottom walls of the chambers 9 to be drawn around said chambers and into the engine cylinders in the manner 100 above explained. The exhaust manifold 18 is of course connected to the outlet openings of the casing 5 to exhaust the gases in the same manner as in the embodiment of the invention shown in Fig. 1. 105

From the foregoing description taken in connection with the accompanying drawings, the construction, manner of operation and several advantages of my invention will be clearly and fully understood. The improved vaporizer is of very simple construction, and while it is designed primarily for use in connection with the Ford type of motor vehicle engine, it is apparent that by resorting to minor structural alterations, the 110 device might be adapted for use in connection with various other types of such engines. In practice, it has been found that the device satisfactorily accomplishes the intended purpose and enables the engine to be 115 operated on low grade hydrocarbon fuels with a maximum of power efficiency. As such fuels are procurable at considerably less cost than the refined hydrocarbon fuels, the economy resulting from the use of the 120 device will be at once manifest. The construction and relative proportions of the several parts of the vaporizer as indicated in the accompanying drawings, I have found to be productive of the best results. It is 125 130

however to be understood that the several structural features of the device are susceptible of numerous modifications, and I accordingly reserve the privilege of adopting 5 all such legitimate changes therein as may be fairly embodied within the spirit and scope of the invention as claimed.

Having thus fully described my invention, what I claim and desire to secure by Letters 10 Patent is:—

1. A fuel vaporizer for internal combustion engines comprising a casing having an intake chamber and a plurality of spaced non-communicating exhaust receiving chambers within said intake chamber, and baffle means within the intake chamber to cause a circuitous travel of the mixture in contact with the walls of the exhaust chambers first in one direction and then in a relatively opposite direction to the engine cylinders. 15
2. A fuel vaporizer for internal combustion engines comprising a casing having an intake chamber and a plurality of spaced non-communicating exhaust receiving chambers within said intake chamber, and mixture inlet and outlet openings in the opposite walls of said casing and at one end of each exhaust chamber, the walls of said exhaust chambers constituting baffles to cause a circuitous travel of the mixture first in one direction and then in a relatively opposite direction around and in contact with the walls of the exhaust chambers to the engine cylinders. 25
3. A fuel vaporizer for internal combustion engines comprising a casing having an intake chamber and a plurality of spaced non-communicating exhaust receiving chambers within the intake chamber and having their walls integral with the walls of said casing to constitute baffles to cause a circuitous travel of the fuel mixture first in one direction and then in a relatively opposite direction around and in contact with the walls of the exhaust chambers to the engine cylinders. 30
4. A fuel vaporizer for internal combustion engines comprising a casing having an intake chamber and spaced non-communicating exhaust receiving chambers within said intake chamber, and baffle means arranged between the spaced exhaust chambers to cause a circuitous travel of the mixture in contact with the walls of said chambers to the engine cylinders. 35
5. A fuel vaporizer for internal combustion engines comprising a casing having a mixture intake chamber and provided with mixture outlets for connection to the engine cylinders, spaced exhaust receiving chambers within said intake chamber and between the outlets, and baffles opposed to the mixture outlets to cause a circuitous travel of the gas around the respective exhaust chambers to the outlets. 40
6. A fuel vaporizer for internal combustion engines comprising a casing having a mixture intake chamber and provided with outlets for connection to the engine cylinders, spaced exhaust receiving chambers within said intake chamber each having a transverse wall integrally connected to the opposite side walls of the casing, and a baffle wall opposed to each of the mixture outlets to cause a circuitous travel of the fuel mixture around the exhaust chambers to said outlets. 45
7. A fuel vaporizer comprising a casing having an intermediate mixture intake chamber and an exhaust receiving chamber at each end of said intake chamber, the side walls of said casing having mixture inlet and outlet openings, an additional exhaust receiving chamber within the intake chamber and extending longitudinally between the mixture inlet openings, and baffle walls within said intake chamber between the inlet and outlet openings against which the incoming mixture impinges and by which it is caused to travel circuitously around the exhaust receiving chamber to the outlet openings. 50
8. A fuel vaporizer for internal combustion engines comprising a casing having an intermediate mixture intake chamber and exhaust receiving chambers at opposite ends of said intake chamber, said casing being provided in its side walls with spaced mixture inlet and outlet openings respectively, additional exhaust receiving chambers within the intake chamber and extending between the spaced inlet and outlet openings, and baffle walls between the opposed inlet and outlet openings and extending longitudinally between one of the latter exhaust chambers and one of the first named exhaust chambers to cause a circuitous travel of the incoming mixture through the intake chamber and around the exhaust chambers to the outlet openings. 55
9. A fuel vaporizer for internal combustion engines comprising a casing having a mixture intake chamber and inlet and outlet openings in the side walls of the casing at the opposite ends of said chamber, longitudinally spaced exhaust receiving chambers within said intake chamber and having their walls integral with the side walls of said casing, the longitudinal walls of said exhaust receiving chambers being spaced from the corresponding walls of the casing, and baffle means extending longitudinally from one end of each of the exhaust receiving chambers between the opposed mixture inlet and outlet openings to cause a circuitous travel of the incoming mixture through the intake chamber around said exhaust receiving chambers to the outlet openings. 60
10. A fuel vaporizer for internal com- 130

bustion engines comprising a casing having a mixture intake chamber common to all of the engine cylinders and opposed mixture inlet and outlet openings in the side walls of said casing, a longitudinally extending exhaust receiving chamber within said intake chamber, and a baffle at one end of the exhaust chamber interposed between the opposed mixture inlet and outlet openings to cause a longitudinal travel of the incoming mixture around the exhaust chamber to the outlet opening.

11. The combination with an internal combustion engine having a mixture intake manifold, of a casing interposed between the intake manifold and the engine cylinders and having an intake chamber common to all of the engine cylinders and mixture inlet and outlet openings in the side walls of the casing communicating with said chamber, an exhaust receiving chamber within the intake chamber and extending longitudinally thereof, and baffle means within the intake chamber against which the incoming mixture impinges to cause a circuitous travel of the mixture longitudinally through the intake chamber around the exhaust chamber to the outlet opening.

12. A fuel vaporizer for internal combustion engines comprising a single unitary structure having an intake chamber, spaced exhaust receiving chambers, and a wall connecting adjacent walls of the exhaust chambers to cause a circuitous travel of the mix-

ture in contact with the walls of the exhaust chambers to the cylinder ports of the intake chamber.

13. A fuel vaporizer for internal combustion engines comprising a single unitary structure having an intake chamber and a plurality of spaced exhaust receiving chambers to receive the exhaust from the individual engine cylinders, and transverse baffle walls connecting the side walls of the intake chamber and against which the mixture impinges to cause a circuitous travel of the mixture in contact with the walls of the exhaust chambers to the cylinder ports of the intake chamber.

14. A fuel vaporizer for internal combustion engines comprising a unitary structure having an intake chamber and a series of longitudinally spaced exhaust receiving chambers within the intake chamber to receive the exhaust from the individual engine cylinders, and angular transverse baffle walls integrally connecting the side walls of the intake chamber and the adjacent walls of spaced exhaust chambers to cause a circuitous travel of the mixture in contact with the walls of the exhaust chambers to the cylinder ports of the intake chamber.

In testimony whereof I affix my signature in the presence of two witnesses.

FRANKLIN E. ARNDT.
